UNITED STATES PATENT OFFICE.

IRA S. McNAUGHT, OF CHICAGO, ILLINOIS.

ADJUSTABLE TRACK FOR SLIDING DOORS.

No. 921,440.

Specification of Letters Patent. Patented May 11, 1909.

Application filed June 5, 1907. Serial No. 377,380.

To all whom it may concern:

Be it known that I, IRA S. McNAUGHT, a citizen of the United States, residing at Chicago, in the county of Cook and State of Illinois, have invented certain new and useful Improvements in Adjustable Tracks for Sliding Doors, of which the following is a specification.

The invention relates to improvements in adjustable tracks such as are used in combination with hangers carrying sliding doors, and the invention consists in the means supporting the track for adjusting the vertical position of the door.

When a track for a sliding door is secured to its support, and a door suspended therefrom, one end of the track lies concealed behind the partitions between which the door is adapted to slide. For various reasons, such as the warping of a beam to which the track may be secured or the settling of the floor, or the partitions on either side of the track losing their alinement if the track is secured to the same, the door loses its proper vertical position relative to the floor so that it does not slide freely.

One of the objects, therefore, of the invention is to provide means for readily adjusting the track so as to bring the door into its proper vertical position, without removing the track from its support, or removing any of the adjacent parts relative thereto.

In the accompanying drawing, Figure 1 is a side elevation of my adjustable track, having a door slidably connected thereto, with the partitions inclosing the track broken away; Fig. 2 is an end elevation of the upper portion of Fig. 1 at the left end thereof; Fig. 3 is a view similar to Fig. 1 showing a modified form of my invention; and Fig. 4 is a cross section on line 4—4 of Fig. 3.

Referring now more specifically to the drawings, 5 represents a track of tubular form, having a longitudinal slot at the bottom thereof and adapted to coöperate with a hanger secured to a door, that will be hereinafter described. As a means for supporting the track a series of brackets 7 are used which partially encircle the track and are adapted to have a sliding engagement therewith so that they may be moved to any suitable position on the track. Each bracket is provided with a hanger arm 8, that is preferably formed integral with the bracket por-

tion 7, which arm 8 is provided on one of its edges with ratchet teeth 9.

10 represents a support for the track, and to which are secured a series of plates 11 by means of the screws 12, said plates having keepers 13 on the outer faces thereof 60 preferably formed integral therewith and through which the hanger arms 8 are adapted to pass.

Pivotaly mounted within the keepers 13 are clamps herein shown as in the nature 65 of pawls 14 having ratchet teeth 14^a on one edge adapted to engage the ratchet teeth 9 on the hanger arms, said engagement between the teeth being effected by a movement of the pawl 14 in one direction, and a 70 disengagement therefrom by a movement in the opposite direction, said pawls being pivoted by means of the pins 15 passed through the plates 11 and keepers 13. Each pawl is provided with an arm 16, and pivotally attached to each arm 16 is a connecting rod 16^a, one end of which terminates at the opening of the doorway, and has a lever arm 17 pivoted thereto by means of the pivot pin 18. A pivot bolt 19 secures the lever arm 80 17 to the support 10, which lever arm extends down below the support 10 so that the same may be readily grasped. As a means for securing the lever arm in any set position a segment 20 is provided having a slot 21 there- 85 in and a sliding bolt 22 is connected to the lever arm and extends through the slot 21 of the segment 20, having a wing nut 23 thereon so that by a movement of the wing nut the lever arm may be drawn against the segment 20 or released therefrom. In Fig. 1 the device is shown with ratchet teeth in engagement and the track in locked position, whereas in Fig. 3 the lever arm has been moved to the left, thereby moving the arms 95 of the pawls to the right, and consequently throwing the ratchet teeth out of engagement whereupon the track may be alined.

When the track is in its proper position to afford the right vertical adjustment of the 100 door, the lever is thrown to the right, as viewed in Fig. 1, and the parts are firmly locked.

It is sometimes difficult, especially where heavy doors are used, to adjust the track in 105 its proper position as the door has to be supported while so doing, and therefore in Figs. 3 and 4 I have shown a modified form of in-

vention wherein there is disposed substantially centrally of the track a bracket 24 having a horizontal lug 25 formed integral therewith, which lug is apertured to receive a bolt 26 that has a threaded engagement with a support 27 secured to the support 10 by means of the screws 28. In this construction to raise or lower the track to its proper position the screw 26 may be either moved up or down thereby adjusting the door relative to the floor and affording an intermediate support readily accessible so as to permit either end of the track to be rocked to secure the proper alinement of the track parallel with the floor.

In the drawings 29 represents the partition concealing the back portion of the track; 30 is a door to which are secured hangers 31 having wheels 32 journaled thereon and moving within the tubular track, while 33 is a partition at the outer end of the track, the space between the two partitions constituting the doorway, and 40 represents the floor. It is to be understood, however, that more than two supports may be used, and where the track requires more than two of said supports the arms of any additional pawls may be connected to the rod 16^a, the same as the arms 16 are connected. Nor is the invention limited to the use of teeth on the edges of the hanger arms and pawls since the latter have a clamping action as well as a positive holding action, and a frictional surface or contact might serve equally as well as the ratchet teeth, and therefore without confining myself to the specific construction shown,

I claim:

1. In a door hanger the combination of a support, a clamp member pivotally secured thereto, a track, a bracket secured to said track, and means for moving said clamp

member whereby said bracket is clamped against said support, substantially as described.

2. In a door hanger the combination of a support, clamp members pivotally secured thereto, a track, brackets secured to said track, and means for simultaneously moving said clamp members whereby said brackets are clamped against said support, substantially as described.

3. In a door hanger the combination of a support, pawls provided with teeth pivoted to said support, a track, brackets secured to said track, said brackets provided with teeth, and means for moving said pawls whereby the teeth on said pawls and brackets coöperate to hold said track in locked position, substantially as described.

4. In a door hanger the combination of a support, pawls provided with teeth pivoted to said support, a track, brackets secured to said track and provided with teeth adapted to coöperate with the teeth on said pawls, and means for simultaneously moving said pawls to secure said track in the proper vertical position relative to said support, substantially as described.

5. In a door hanger the combination of a support, pawls pivotally secured to said support provided with teeth, a track, brackets secured to said track and provided with coöperating teeth, a rod secured to said pawls for simultaneously moving said teeth into engagement or disengagement for the purpose of adjusting said track relative to said support, and means for operating said rod and holding the same in adjusted position.

IRA S. McNAUGHT.
